United States Patent Office.

JAMES WHAIT, OF SPRINGFIELD, MISSOURI.

Letters Patent No. 65,624, dated June 11, 1867.

IMPROVED FOOT-SCRAPER.

The Schedule referred to in these Letters Patent and making part of the same.

TO ALL WHOM IT MAY CONCERN:

Be it known that I, JAMES WHAIT, of Springfield, Missouri, have invented certain new and useful improvements in Scrapers for Cleaning Boots and Shoes; and I hereby declare that the following is a true, full, and exact description of the same, reference being had to the accompanying drawings, and to the letters of reference marked thereon,

Figure 1 in the annexed drawings, which make a part of this specification, represents a front view of my scraper.

Figure 2 is a plan view of the concave adjustable jaw.

Figure 3 is an end view of the clamp.

The letter A, in fig. 1, designates the base of the scraper, which will be fastened to the step by screws; B represents the scraper, which consists of a vertical plate of iron, cast solid with the base A. Near the ends of A are the flanges C, which are cast solid with scraper B and base A, and intended in part to give additional strength to said scraper. In a line with flanges C are placed the vertical clamps D, each of which is composed of two jaws, one of each brace of jaws being cast solid with scraper B, and the two opposite jaws being hinged to their respective flanges and confined together near their top by a screw-bolt, g. The jaws D are concave to within a short distance of their top, but leaving a plane surface of near the eighth of an inch in width on the face of the jaw. It will be observed that when the jaws are screwed together the material within them will be compressed by the flat margin of the jaws, and will, consequently, expand in the concave, and thus hold the shucks firmly in position.

In operating my scraper, first unscrew the bolt that holds the jaws together, then insert between them the shucks or rags previously prepared for the purpose. This being done, screw up the nut as far as it will go, and the scraper will be ready for use, and will clean the sides of shoes or boots, as well as the bottom.

Having thus described my invention, what I claim, and desire to secure by Letters Patent, is—

The hinged hollow sides D D, in combination with scraper B, all constructed and arranged as and for the purpose set forth.

JAMES WHAIT.
